UNITED STATES PATENT OFFICE.

LUCIEN I. BLAKE, OF LAWRENCE, KANSAS.

SIGNALING BETWEEN VESSELS UPON WATER.

SPECIFICATION forming part of Letters Patent No. 506,150, dated October 3, 1893.

Application filed October 1, 1889. Serial No. 325,685. (No model.)

To all whom it may concern:

Be it known that I, LUCIEN I. BLAKE, a citizen of the United States, residing at Lawrence, in the county of Douglas and State of Kansas, have invented certain new and useful Improvements Relating to Submarine Signaling, of which the following is a specification.

The purpose, primarily, is to prevent collisions between vessels in time of fog and at night, by warning them of each other's presence, and in like manner, to prevent shipwrecks by warning vessels of the proximity of a dangerous shore; and a secondary object is to furnish a means of communication between vessels, or between vessels and the shore, independently of the state of the weather.

Having thus mentioned the purpose of my invention, I will proceed to describe it, at first in general and then in detail, reference being made to the accompanying drawings, in which the essential parts of the invention are illustrated.

Figure 1 shows two transverse sections of the hull of a vessel; in the left-hand one there is indicated a sound-producing apparatus which is shown more in detail, in sectional view, in Fig. 3. In the right-hand section of Fig. 1 there are indicated two sound-receiving mechanisms, one of which is shown more in detail, in sectional view, in Fig. 2.

It is a well known fact in science and in practice that the atmosphere is exceedingly uncertain and variable in its capacity for the transmission of sound to any considerable distance; that the wind and the strata of air of varying density hanging over the water obstruct and deflect the sound, so that fog horns and sirens and belis are often unreliable means of signaling even to small distances.

Experience shows that collisions between vessels in the fog or at night generally occur through ignorance on the part of the vessels of each other's presence, although at the time each may be sounding its fog signals. In such cases the air has failed to transmit the sounds or has deflected them away. Water as a medium of communicating sound is not subject to the same difficulty. Sounds are not materially deflected or obstructed by it;

at any rate the conditions of fog and storm that make the atmosphere utterly unreliable as a sound transmitter do not seriously affect the conductivity of the water. It is upon this 55 superiority of water as a sound medium that I rely in my invention.

In its general form, my method embraces, first, the production in the water of certain sounds, constituting characteristic and intelligible signals, by means of suitable appliances located upon the vessel, or connected with the shore as the case may be; second, the transmission of these sound signals by and through the water to distances limited only 60 by the intensity of the sounds; third, the reception of these sound signals out of the water by a suitable appliance which I have chosen to designate by the term "hydrophone."

I will first proceed to a description of the 70 hydrophone. I have proved by experiment that sound vibrations traversing the water will impart themselves to and will pass through a submerged diaphragm of metal even if several inches thick. Taking advantage of this fact, the hydrophone consists essentially of a plate, preferably of metal, having an area from several square inches to several square feet, according to circumstances of application, and a thickness sufficient to 75 resist the pressure and commotions of the water in which it may be immersed, and the striking of foreign substances; as ice, &c., against it. This plate, in the preferred construction, serves as a diaphragm to a resonance chamber, whose other sides may be of any suitable material and whose shape and size may be suitably varied to adapt the structure to the special conditions of its use. Connected with and projecting from this resonance chamber are one or more ear-tubes or 80 sound conductors, leading to any place or places in the vessel convenient for an observer. Preferably the observer's room should be placed low down in the hull, so as to be 85 affected as little as possible by the dash of the waves.

While, as above indicated, the sound-receiving diaphragm is preferably of metal, yet manifestly other sonorous materials may be 90 used therefor; and so also, instead of inserting a special plate of sonorous material in an

- aperture formed in the walls of a vessel, the walls themselves, or a selected portion of the walls—especially in the case of iron or steel vessels—may be utilized as a diaphragm, the part thus selected being made to form one side of a resonance chamber constructed immediately behind it, or being made otherwise to receive upon its inner face the sound-receiving apparatus.
- 10 In the vessel's interior, and against the side or portion of the side selected as the diaphragm, or against the inserted plate, is built the resonance chamber. Any sound vibrations traversing the water will be communicated to and will produce corresponding molecular vibrations in the diaphragm. These vibrations of the diaphragm incite sonorous vibrations in the air column of the hydrophone, which in turn are communicated by 15 the ear-tubes to the ear of the observer. Sounds feeble in the water are thus intensified and rendered efficient as signals. By employing two or more hydrophones, placed in different parts of a vessel, with ear-tubes 20 communicating to a common place of observation, the direction of the origin of the sound signals may be determined, and thus the direction or position of a vessel or of the shore may be more accurately determined.
- 25 The resonance chamber of the hydrophone, although receiving all sounds, intensifies sounds of one particular pitch above all others. If the sounds employed as signals are predominantly of the fundamental pitch of 30 the hydrophone, then is the sensitiveness of the hydrophone intensified in regard to them, and other sounds extraneous and disturbing are relatively deadened. The accuracy in the reception of the signals is thus increased.
- 35 Referring to the drawings, A, in Fig. 1, respects the hull of a ship in which there are shown two hydrophones, B, B, with sound tubes, c c, leading from the resonance chambers to the observer's room D. The construction of the hydrophone is shown more in detail in Fig. 2, in which E is a metallic plate bolted to the walls of an opening in the side of a wooden vessel; F being a resonance chamber constructed upon the interior of said 40 plate, and c the sound tube leading thence to the observer's station.
- 45 In place of the purely mechanical hydrophone just described, an electro-mechanical hydrophone, of the nature of a telephone, may be constructed as follows: In lieu of the ear-tubes (the other parts of the mechanical hydrophone remaining the same) a circular outlet is made in the resonance chamber, six inches more or less in diameter, over which a thin membrane of any suitable elastic material as goldbeater's skin, or any light thin metal, is tightly stretched. Connected with 50 this membrane, or formed in part by it, may be arranged a microphone or electrical sound-transmitter, in circuit with any suitable telephonic receiver, so that vibrations of the air column of the hydrophone may be communicated to the microphone and thus to the telephone located in any convenient part of the vessel. Further, the resonance or air chamber may be entirely dispensed with, and the microphone attached directly to the diaphragm in the walls of the vessel; in which case, the molecular vibrations of the diaphragm, which have been produced by the sound signals arriving through the water are directly the exciting cause of the microphonic action, without an intermediate pulsating air column.

55 The preferred mode of producing the signals, and this in itself is a distinctive part or feature of the invention, is by the use of some apparatus, such for instance as a water siren which will produce a rapid and regular succession of blows upon the water, and will 60 thus create a musical tone, as distinguished from a more ordinary and undefined sound. Such sounds as have a distinguishable pitch or are characterizable as musical sounds or tones will be found to have much greater 65 penetrating power than any others.

70 A water siren I define as an apparatus such as an ordinary siren in which the usual air or steam jet is replaced by a water jet and whose disk may be revolved by power other than that of the issuing water. The whole siren may be immersed in the water about the vessel, and by means of short and long blasts and pauses the Morse telegraphic code may be employed for communication. Such a construction of siren is shown, in vertical section, in Fig. 3 of the drawings. G is a disk of metal mounted on a shaft to which is attached a pulley for driving it by any available power at the required speed. This disk 75 is pierced with a series of holes which as the disk revolves register periodically with holes piercing the wall of the vessel. H is a chamber surrounding the disk and constitutes the channel whereby water or steam forced 80 through the feed tube I is delivered to the face of the disk. This siren is shown in elevation on a smaller scale in the vessel K of Fig. 1.

85 Although in the two views, Figs. 2 and 3, the siren and the hydrophone are shown as having approximately the same area, yet in actual construction it will be found that the siren can be made very much smaller than the sound receiver.

90 It will of course be understood from what has been said above, that, for the purpose of enabling passing vessels to communicate with the shore and to receive signals therefrom, a suitable submerged diaphragm together with a suitable sound producing apparatus, constructed on the plan of the hydrophone and of the sound transmitter above described, may be established near to and in communication with the shore station.

95 What is claimed as new is—

1. The hereinbefore described improvement in the art of submarine signaling, which consists in producing in the water, by means

of a rapid and regular succession of blows or impulses thereon musical sounds or tones, and taking up the vibrations by a suitable submerged receiving instrument.

5 2. In combination with the walls of a ship or other vessel, and forming a part of the same, a submerged diaphragm and sound receiving apparatus as herein set forth, as a means of taking up sound vibrations transmitted through the water.

3. In combination with a submerged diaphragm placed in and forming a part of the walls of a ship or other vessel, a resonance

chamber, for reinforcing the sound vibrations taken up from the water.

4. The combination of a submerged diaphragm placed in or forming a part of the walls of a ship or other vessel, and a resonance chamber which is attuned to the pitch of a sound producing apparatus placed on the shore or on another vessel.
